CLAIM

The ornamental design for a vacuum suction cup, as shown and described.

DESCRIPTION

FIG. 1 is a front, right side, bottom perspective view of a vacuum suction cup, showing my new design;

FIG. 2 is a front, left side, top perspective view thereof;

FIG. 3 is a rear, left side, top perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines in the figures illustrate portions of the vacuum suction cup that form no part of the claimed design.

1 Claim, 9 Drawing Sheets
